No. 781,716.

PATENTED FEB. 7, 1905.

W. W. DENNIS.
PNEUMATIC CAR BUFFER.
APPLICATION FILED APR. 22, 1904.

UNITED STATES PATENT OFFICE.

WILLIAM W. DENNIS, OF CINCINNATI, OHIO.

PNEUMATIC CAR-BUFFER.

SPECIFICATION forming part of Letters Patent No. 781,716, dated February 7, 1905.

Application filed April 22, 1904. Serial No. 204,389.

To all whom it may concern:

Be it known that I, WILLIAM W. DENNIS, a citizen of the United States, residing at East Norwood, Cincinnati, in the county of Hamilton and State of Ohio, have invented certain new and useful Improvements in Pneumatic Car-Buffers, of which the following is a specification.

This invention provides a special construction of buffer for use particularly on railway-cars or in similar adaptations for absorbing and reducing the vibration, shock, or jar consequent to the starting and stopping of a train and caused by bumping of the cars one against the other.

The buffer consists, preferably, of pneumatic cushion means coöperating with a piston or the like which carries the coupling devices to accomplish the desired results above outlined.

For a full description of the invention and the merits thereof and also to acquire a knowledge of the details of construction of the means for effecting the result reference is to be had to the following description and accompanying drawings.

While the essential and characteristic features of the invention are susceptible of modification, still the preferred embodiment of the invention is illustrated in the accompanying drawings, in which—

Figure 1 is a side elevation of a buffer embodying my invention. Fig. 2 is a broken view showing more clearly the arrangement of the inlet and outlet pipes leading into the cylinder, said view being partially in section. Fig. 3 is a vertical sectional view showing more clearly the construction of the puppet-valve carried by the secondary air-pipe which communicates with the cylinder. Fig. 4 is a view similar to Fig. 3, showing the somewhat-modified construction of puppet-valve utilized to govern the outlet by which the air in the cylinder is permitted to pass therefrom. Fig. 5 is a transverse sectional view, partially broken away, taken about on a line 5 5 of Fig. 3.

Corresponding and like parts are referred to in the following description and indicated in all the views of the drawings by the same reference characters.

Generally describing my invention, the same consists of an air-cylinder 1, which is suitably mounted upon the under side of a car-body 2, in which is located the piston 3. Air is admitted into the cylinder 1 through a main supply-pipe 4, which leads from a suitable compressed-air reservoir, and the amount of air admitted into the cylinder is controlled by suitable valve means adapted to be operated by the engineer of the train. The main supply-pipe 4 leads into the cylinder at a suitable point between the ends of the latter, and a check-valve is disposed in the length of the pipe 4 at a point adjacent the cylinder 1 aforesaid. My invention embodies also a peculiar arrangement of air-pipes by which the air is admitted into and conducted from the cylinder 1 and peculiar valve means for governing the admission and outflow of the air in a manner which will be described more fully herein-after.

It is designed to utilize any suitable form of coupler in connection with my buffer, and this coupler (designated 5 in the drawings) is preferably carried by the piston-rod 6 of the piston 3, so that in the bumping of the cars as the train starts and stops the jar received by the coupling means will be directly taken up by means of my pneumatic buffer. The secondary air-pipe 7 is mounted upon the cylinder, being provided with a branch outlet-pipe 7^a and a branch inlet-pipe 7^b. The pipe 7 is merely a conducting-pipe through which the air which has been admitted into the cylinder 1 through the main supply-pipe 4 may pass from one end of the cylinder to the other end thereof, or, in other words, from one side of the piston 3 to the other side thereof. A puppet-valve 8 is disposed in the length of the branch pipe 7^a, its valve-plug 8^a being mounted in a casing 9 and normally remaining seated against a valve-seat 10, provided in said casing. The valve 8 is normally held closed, so as to prevent the air admitted into the cylinder 1 from escaping therefrom until this is compressed to such an extent as to cause automatic opening of the valve 8, and the compression of the air in the cylinder, which causes opening of the valve 8, is of course due to the buffing movement of the piston 3. Projected from

the valve-plug 8^a are guide-rods 11, which latter are rigidly mounted upon the said plug, being adapted to carry an adjustable plate 12. A spring 15 is interposed between the plate 12 and the valve-plug 8^a, and this spring normally tends to hold the valve closed until the tension thereof has been overcome due to increase in pressure of the air within the cylinder 1 as caused by movement of the piston 3. 5 The supporting-plate 12 is held rigidly at an ascertained adjustment by means of an adjusting member 13, the latter being a screw member of any suitable type. The supporting-plate 12 is prevented from displacement 10 from the guide-rods 11 by heads 14, provided upon said rods 11. Owing to the adjustability of the tension of the spring 15, it will be noted that the valve 8 may be caused to unseat at different degrees of pressure of the air 15 within the cylinder 1, so as to admit of outflow of this air through the secondary air-pipe 7 and back into the cylinder through the branch pipe 7^b. A check-valve 16 is carried by the secondary air-pipe 7, so as to prevent back- 20 flow of the air in the cylinder 1 through the said secondary pipe 7. An outlet-pipe 17 leads from the end of the cylinder 1 opposite to that adjacent which the outlet branch pipe 7^a is located, and a puppet-valve 18 governs 25 the egress of the air from the cylinder 1 through the pipe 17. The puppet-valve 18 is of a form similar to the valve 8, before described, also having a valve-plug 8^a mounted in a valve-casing 9 and provided with guide- 30 rods 11. This valve is spring-operated and is adapted to open at varied heights in the pressure of the air within the cylinder 1 by means of adjustment of the spring 15 adjacent thereto, which spring is operated upon by 35 members 12 and 13, which have been before described. The air, however, which passes the puppet-valve 18 escapes from the valve-casing 9 thereof through outlet-openings 19 in the lower end of said casing. The adjustable members 13, which coöperate with the tension-adjusting plates 12, are mounted in tubular members 20, suitably disposed at the lower portions of the valve-casings 9, as shown 40 in Figs. 4 and 5, and ready access may be had 45 for adjustment of the member 13, which co-operates with the puppet-valve 8, by removal of a screw-cap 21, which normally houses the said member. The adjusting members 13 are provided with finger-pieces 22 at their lower 50 ends, by which said members may be properly manipulated. The adjusting member 13 of the puppet-valve 18 has its lower end exposed and not housed by any parts as described with reference to the adjusting member 55 13 of the puppet-valve 8.

In the practical operation of my invention preparatory to stopping the train the engineer or other operator, as the case may be, by operation of proper mechanism admits air 60 into the cylinder 1 through the main supply-

pipe 4, this air passing into the end of the cylinder designated *b*, as illustrated in the drawings. The air cannot pass back through the supply-pipe 4 owing to the operation of a suitable check-valve 23, and it may be here 70 said that it is designed to utilize any suitable form of check-valve in connection with my invention. As the train slackens in speed the bumping movement of the cars causes actuation of the piston toward one end of the cylinder 75 —namely, that indicated by the letter *b*—and the air in the cylinder forms a cushion for the piston in a manner which will be readily comprehended. As the piston 3 is gradually forced toward the end *b* of the cylinder 80 1 in the above movement the air in the piston is compressed until the pressure thereof causes the puppet-valve 8 to open, thereby admitting of passage of this air through the secondary air-pipe 7 in the other end of 85 the cylinder, which for purposes of this description is indicated at *a*. The air which passes the puppet-valve 8 into the end *a* of the cylinder is prevented from passing back from the secondary air-pipe 7 by the check- 90 valve 16 adjacent the branch inlet-pipe 7^b. When the piston 3 nears the end *b* of the cylinder 1, same closes the outlet-pipe 7^a when said piston reaches an ascertained point in its movement, a sufficient amount of air remaining in the end *b* of the cylinder, however, to form an efficient cushion therefor to receive the jar of the sudden stopping of the train. As the train starts, the piston 3 begins to move, because of the coupler connections with 95 the piston-rod 6, toward the end *a* of the cylinder 1, gradually compressing the air in this end of the cylinder. When the pressure of the air in the end *a* of the cylinder 1 reaches an ascertained height in the starting move- 100 ment of the train, the puppet-valve 18 opens so as to gradually admit of escape of the air from the cylinder through the outlet-pipe 17 and openings 19. When the piston in its last-described movement reaches a point ad- 105 jacent the end *a* of the casing, so as to close the entrance to the outlet-pipe 17, the remaining air is prevented from passing off through this pipe 17 and constitutes a cushion or buffer, 110 as will be readily seen.

In order to limit the movement of the piston and prevent likelihood of the shock of the cars being received by the cylinder-heads of the cylinder 1, the piston-rod 6 is provided in its length with stop members in the form of 115 flanges 24, and these members coöperate with a rigid hanger 25 to limit the longitudinal movement of the piston 3 and prevent contact of this piston with the heads of the cylinder 1, above mentioned. In order to prevent turning movement of the coupler 5, the piston-rod 6 is preferably squared in its length, passing through a squared opening in the hanger 120 25. The coupler 5 of one car is thus always held in a position ready to engage the coupler 125 130

carried by the other car. It is designed that a single pneumatic buffer be used at one end of each car, and the buffer, as above set forth, effectually absorbs the motion and deadens the shock arising, thus lengthening the life of the cars, as well as the couplers used thereon. The length of the stroke of the piston would not be much, but will be varied somewhat as found best, and the amount of air always confined in the cylinder will of course be determined by the distance between the ends of the cylinder, and the outlet-pipes 7^a and 17 will lead therefrom.

Having thus described the invention, what is claimed as new is--

1. In a pneumatic car-buffer, the combination of a cylinder, a piston operating in said cylinder, a piston-rod adapted to receive a buffering shock, a main supply-pipe leading into the cylinder, a secondary pipe leading from a point adjacent one end of the cylinder into the cylinder at a point adjacent the opposite end thereof, a puppet-valve controlling the passage of a pressure medium through the secondary pipe aforesaid, and a second puppet-valve governing the escape of the pressure medium from the cylinder.

2. In a pneumatic car-buffer, the combination of a cylinder, a piston movable therein, a piston-rod, a coupling or buffering member carried by said piston-rod, a main pipe for supplying a pressure medium to the cylinder, a secondary pipe or passage-way for conducting the pressure medium from one side of the piston to the other, and valve means governing the outflow of the pressure medium from the cylinder.

3. In a pneumatic car-buffer, the combination of a cylinder, a piston, a piston-rod, a coupling or buffering member disposed upon said rod, a main supply-pipe for conveying a pressure medium into the cylinder, a secondary pipe for conducting the pressure medium from one side of the piston to the other, puppet and check valves in the length of the secondary pipe aforesaid, an outlet-pipe leading from the cylinder, and valve means governing egress of the pressure medium through the outlet-pipe.

4. In a pneumatic car-buffer, the combination of a cylinder, a piston movable therein, a piston-rod extending from the piston and carrying a car-coupler or similar parts, a main supply-pipe for conducting a pressure medium into the cylinder, a secondary pipe having outlet and inlet branches communicating with the cylinder, a puppet-valve governing the passage of the pressure medium through the outlet branch of the secondary pipe aforesaid, a check-valve disposed in the length of said secondary pipe, an outlet-pipe leading from the cylinder, and a puppet-valve governing the outflow of the pressure medium through the outlet-pipe aforesaid.

5. In a pneumatic car-buffer, the combina-

tion of a cylinder, a piston movable in said cylinder, a piston-rod, a coupler mounted on said piston-rod, a main supply-pipe leading into the cylinder at a point between the ends thereof, a secondary pipe having outlet and inlet pipes leading into the cylinder, a puppet-valve governing the outlet of the pressure medium through the outlet-pipe of the secondary pipe aforesaid, a check-valve carried by the secondary pipe, an outlet-pipe to admit of escape of the pressure medium from the cylinder, and valve means governing the egress of the pressure medium through the outlet-pipe aforesaid.

6. In a pneumatic car-buffer, the combination of a cylinder, a piston movable therein, a piston-rod, a coupler carried by the piston-rod, a main supply-pipe having a pressure medium leading into the cylinder at a point between the ends thereof, a secondary pipe provided with a branch outlet-pipe leading into the cylinder adjacent one end thereof and having an inlet-pipe leading into the cylinder between the ends of said cylinder, a puppet-valve disposed in the length of the branch outlet-pipe, a check-valve carried by the secondary pipe, and an outlet-pipe leading from the end of the cylinder opposite that adjacent which the branch outlet-pipe aforesaid is disposed.

7. In a pneumatic car-buffer, the combination of a cylinder, a piston disposed in said cylinder, means for supplying a pressure medium to the cylinder, means for conducting the pressure medium from one end of the cylinder to the other and from one side of the piston to the other, a piston-rod carried by the piston, and means for limiting the movement of the piston-rod independently of the cylinder.

8. In a pneumatic car-buffer, the combination of a cylinder, a piston disposed in said cylinder, means for supplying a pressure medium to the cylinder, means for conducting the pressure medium from one end of the cylinder to the other and from one side of the piston to the other, a piston-rod carried by the piston, and stop means carried by the piston-rod and limiting the movement thereof.

9. In a pneumatic car-buffer, the combination of a cylinder, a piston disposed in said cylinder, means for supplying a pressure medium to the cylinder, means for conducting the pressure medium from one end of the cylinder to the other and from one side of the piston to the other, a piston-rod carried by the piston, and stop members projected from the piston-rod and adapted to limit the movement of the said piston-rod.

10. In a pneumatic car-buffer, the combination of a support, a cylinder, a piston mounted in said cylinder, a piston-rod, a coupler disposed upon the piston-rod, means for supplying a pressure medium to the cylinder, means for governing the outflow of the pressure me-

dium from the cylinder, a rigid hanger carried by the support aforesaid, and stop members projected from the piston-rod and coöperating with said rigid hanger to limit the movement 5 of the piston-rod and piston.

11. In a pneumatic car-buffer, the combination of a cylinder, a piston movable therein, a piston-rod, a coupling or buffering member carried by the piston-rod, means for supplying a pressure medium to the cylinder, puppet-valves governing the egress of the pressure

medium from the cylinder, spring means for normally holding the puppet-valves closed, means for adjusting the tension of the spring and means aforesaid for the purpose set forth. 15

In testimony whereof I affix my signature in presence of two witnesses.
